UNITED STATES PATENT OFFICE.

LOUIS JENSEN, OF CHICAGO, ILLINOIS, ASSIGNOR TO UNITED AUTOGRAPHIC REGISTER CO., OF CHICAGO, ILLINOIS, A CORPORATION OF ILLINOIS.

PAPER-FEEDING MECHANISM.

1,407,424.

Specification of Letters Patent. Patented Feb. 21, 1922.

Application filed June 3, 1921. Serial No. 474,630.

To all whom it may concern:

Be it known that I, LOUIS JENSEN, a citizen of the United States of America, and a resident of Chicago, county of Cook, and 5 State of Illinois, have invented certain new and useful Improvements in Paper-Feeding Mechanism, of which the following is a specification.

This invention relates to paper feeding 10 mechanism for typewriting machines which are intended for writing upon perforated paper record strips, the perforations on the strips being in pairs spaced apart at regular predetermined lengths of the strips according 15 to the printed forms thereon. The object of the invention is to maintain correct registration between the forms on the paper. This object is accomplished by the use of two pairs of coacting feed rollers for acting 20 upon the paper web along lines passing lengthwise along the paper through the perforations therein. The feed rollers become inoperative when the perforations arrive between and are centered by the rollers. 25 When a pair of perforations are between the two pairs of feed rollers, continued rotation of the feed rollers is ineffective for moving the paper and for this reason a central pair of normally inoperative feed rollers 30 are provided by which the paper may again be started in motion.

The purposes of the invention are accomplished by a device such as illustrated in the drawings, in which—

35 Figure 1 is a plan view partly broken away of a typewriting machine with the improved paper feeding mechanism applied thereto.

Fig. 2 is a detail in front elevation of the 40 paper feeding mechanism.

Fig. 3 shows the paper feeding mechanism and the upper part of the typewriter in side elevation.

Fig. 4 is a sectional detail taken on the 45 line 4—4 of Fig. 2.

Fig. 5 is a detail in front elevation and partly in section of the paper feeding mechanism.

Fig. 6 is a sectional detail taken on the 50 line 6—6 of Fig. 5.

Fig. 7 is a sectional detail of one of the pair of paper feeding rollers.

Fig. 8 is a sectional view of the central pair of rollers.

The present design of paper feeding 55 mechanism for typewriting machines is intended for simultaneously feeding a plurality of paper record strips such as are employed for making out bills of lading and for this reason are provided with printed 60 forms and a pair of post holes or perforations for each form for convenience in filing. Heretofore typewriting machines have been used in conjunction with autographic registers for typewriting the forms on these continuous record strips. In the arrangement shown in the present design, the paper is passed over the platen of a typewriting machine, but the platen is preferably fixed on 65 its carriage. The webs of paper pass from 70 the supply rolls over guide rollers on the paper carriage and are drawn over the platen by means of coacting pairs of feed rollers carried by a pair of rotatable shafts. The shafts are geared together to rotate in 75 opposite directions and receive motion from the usual line spacing mechanism of the typewriting machine or from a manually operated wheel fixed to one end of one of the shafts. The coacting feed rollers are arranged in three pairs, a central pair of 80 which is normally inoperative due to the fact that its complementary roller is normally offset therefrom. The remaining two pairs of rollers are respectively spaced laterally from each side of the central pair of rollers and are always in coacting relationship. These side pairs of rollers are so located that during the feed of the paper a pair of perforations on each form of the 85 printed webs will successively arrive between said rollers, at which time the feeding of the paper stops, until the central pair are brought into coacting relationship. The rect registration may be maintained.

Referring to the drawings, the frame 1 of the typewriting machine is shown supporting the carriage 2 on the usual tracks 3. The carriage 2 has provision for supporting 100 a plurality of rolls of paper webs, not shown, but the paper 4 from these rolls passes over guide rollers 5 and through guide 6 and thence upwardly past a platen fixed to the carriage 2. Above the platen 105 are a pair of feed roller shafts 7 and 8 which are geared together by the gears 9 and 10 fast to these shafts. Shaft 7 receives mo-

tion through a ratchet 11 coacting with a feed pawl 12 which has imparted to it an oscillating motion by the line spacing lever 13, or by means of the knurled wheel 14 fast to the end of the shaft. Rotatable with shaft 7 is a sleeve 15 which carries the paper feed rollers 16 and 17. Sleeve 15 is centrally slotted at 18 to receive a pin 19 by means of which a feed roller 20 is secured to shaft 7. The shaft 7 is shiftable lengthwise of the sleeve 15 for moving the feed roller 20 into and out of cooperative relation with the central feed roller 21 fast to shaft 8. In addition to the feed roller 21 the shaft 8 is provided with feed rollers 22 and 23 for respectively coacting with the feed rollers 16 and 17 on shaft 7. When the pair of shafts 7 and 8 are rotated sufficiently to feed the paper the length of a single form, perforations arrive between the rollers 16, 22, and 17, 23 and the feed will momentarily stop irrespective of any continued rotation of these shafts, until the central feed roller 20 is shifted into operative relation with the roller 21. This shifting of the central roller can only be effected when the flat portion 24 thereof is adjacent the roller 21, due to the locking effect of collar 25 on the sleeve 15, except when a pin 26 on shaft 7 arrives opposite the notch 27 in the collar. This notch is so formed that after the pin has entered the same, the continued rotation of shaft 7 will cause the pin to travel outwardly along one edge of the notch and thus again move feed roller 20 out of coacting relationship with the feed roller 21 while these rollers are serving to move the paper far enough to cause it to become engaged by the pairs of rollers 16, 22 and 17, 23. These pairs of rollers are held in resilient engagement by means of springs 30 as shown in Figure 6. These springs serve to urge the shaft 8 toward the shaft 7 according to the tension given the springs by the adjusting screws 31. When it is desired to insert the ends of a new supply of record paper between the feed rollers, the shafts 7 and 8 are separated by rocking the shaft 32 which carries pins 33 for engaging bell crank levers 34 loose on shaft 7, but having cam edges 35 for engaging shaft 8 and forcing it away from the shaft 7.

In the operation of the device the paper is fed as desired by rotating wheel 14 or by means of the line spacing lever 13, either one of which devices will cause the pairs of feeding rolls 16, 22 and 17, 23 to feed the paper until the next pair of perforations become centered between these rollers. If one perforation of a pair arrives between its pair of rollers in advance of the other, as might occur if the paper was fed more rapidly on one side than the other, the remaining pair of rollers might continue to feed

until the paper is again straightened out. When a pair of perforations arrives between these feed rollers, the stopping of the paper advises the operator of the fact that the portion of the record paper which has been written upon is in position to be torn off. This can be effected by means of a knife, not shown, but which may be supported by the frame members 36. To again start the record paper in motion, it is necessary to push inwardly on shaft 7 by means of head 14 to bring the roller 20 into coacting relation with the roller 21. 70

Although but one specific embodiment of this invention is herein shown and described 80 it will be understood that numerous details of the construction shown may be altered or omitted without departing from the spirit of this invention as defined by the following claims. 85

I claim:

1. In a typewriting machine for printing on strips of paper having printed forms of predetermined length, each of which have corresponding post holes adjacent their advance edges, a paper feeding mechanism comprising a pair of coacting friction feed rollers positioned to engage the paper in line with said post holes, and means for moving said strips forward after said post holes have been engaged by said friction rollers. 90

2. In a typewriting machine for printing on strips of paper having printed forms of predetermined length, each of which have corresponding post holes adjacent their advance edges, a paper feeding mechanism comprising two pairs of laterally spaced coacting friction feed rollers, said rollers being positioned to engage the paper along lines passing through said post holes, and means for moving said strips forward after said post holes have been engaged by said friction rollers. 100

3. In a typewriting machine for printing on strips of paper having printed forms of predetermined length, each of which have corresponding post holes adjacent their advance edges, a paper feeding mechanism comprising two pairs of laterally spaced coacting friction feed rollers, said rollers being positioned to engage the paper along lines passing through said post holes, a central pair of rollers, one of which is shiftable into and out of engagement with the remaining roller. 110

4. In a typewriting machine for printing on strips of paper having printed forms of predetermined length, each of which have corresponding post holes adjacent their advance edges, a paper feeding mechanism comprising two pairs of laterally spaced coacting friction feed rollers, said rollers being positioned to engage the paper along lines passing through said post holes, a cen- 125

- tral pair of rollers, one of which is laterally shiftable into and out of engagement with the remaining roller. 25
5. In a typewriting machine for printing on strips of paper having printed forms of predetermined length, each of which have corresponding post holes adjacent their advance edges, a paper feeding mechanism comprising two pairs of laterally spaced co- 10
- 10 acting friction feed rollers, said rollers being positioned to engage the paper along lines passing through said post holes, a central pair of rollers, one of which is shiftable into and out of engagement with the re- 15
- 15 maining roller, said shiftable roller having a flat surface on a portion of its periphery. 6. In a typewriting machine for printing on strips of paper having printed forms of predetermined length, each of which have 20
- 20 corresponding post holes adjacent their advance edges, a paper feeding mechanism comprising two pairs of laterally spaced co- acting friction feed rollers, said rollers being positioned to engage the paper along
- lines passing through said post holes, a cen- 25
- tral pair of rollers, one of which is shiftable into and out of engagement with the re- 30
- 30 maining roller, said shiftable roller having a flat surface on a portion of its periphery, and means for preventing movement of said shiftable roller toward its companion rollers except when said flat portion of the shiftable roller is opposite the companion roller. 7. A typewriting machine comprising a reciprocal carrier, a platen mounted on the same, means for intermittently feeding pre- 35
- 35 determined lengths of a continuous strip of paper therefrom, and friction devices that periodically engage said strip to start the feeding movement of said paper after each stoppage.
- In witness whereof I have hereunto set my hand this 7th day of May, 1921.
- LOUIS JENSEN.
